AARON MOREHOUSE AND ALFRED R. HEATH, OF DANBURY, CONNECTICUT.

Letters Patent No. 94,628, dated September 7, 1869

IMPROVEMENT IN PLAITING-ATTACHMENT FOR SEWING-MACHINES.

The Schedule referred to in these Letters Patent and making part of the same.

To all whom it may concern:

Be it known that we, AARON MOREHOUSE and ALFRED R. HEATH, of Danbury, in the county of Fairfield, and State of Connecticut, have invented a new and useful improved Tucker or Plaiter for Sewing-Machines; and we do hereby declare that the following is a full, clear, and exact description thereof, reference being had to the accompanying drawings, making a part of this specification, in which—

Figure 1 is a side elevation of our improvement, as seen when applied to a machine ready for operation;

Figure 2 is a rear view of the same;

Figure 3 is a plan view of the same;

Figure 4 is a plan view of the lower side of the bent bar, which is immediately beneath the presser-foot of the machine;

Figure 5 is a vertical transverse section of the same, through line E F of fig. 4;

Figure 6 shows the form of the presser-guide before it is bent;

Figure 7 shows the form of the guiding-spring before bending;

Figure 8 shows one form of a clamp for securing the bent arm to the presser-foot of a sewing-machine; and

Figure 9 shows another modification of the sharp-edged gauge used for gauging the distance between the tucks.

Our invention relates to a device for folding the tucks or plaits as they are being sewed with a sewing-machine; and consists in the construction and arrangement of a bent arm, having one or more springs attached, with a gauge, guide, and elevator, whereby the cloth, as it is being passed to the needle in a sewing-machine, is folded and prepared at the same time that the fold or tuck is being sewed, and without any previous manipulation in folding or marking the goods.

This device may readily be attached to any of the sewing-machines now in use, and is an improvement upon the invention for which Letters Patent were granted to us, bearing date the 4th day of August, A. D. 1868, and numbered 80,653.

That others skilled in the art may be able to make and use our invention, we will proceed to describe its construction, and the mode of its operation.

In the drawings—

a represents a bent arm, very similar in its construction to that shown in Letter's Patent No. 80,653, which were granted to us, as already mentioned, except that the arm herein shown is bent in an opposite direction.

This arm, which has the two upright portions *a*³ and *a'*, with a space, *c*, between, has a spring, *c'*, inserted in the space or slot *c*, said spring being secured therein by being soldered at the top, or in any other proper manner.

This spring is shown more fully, as to its form before it is bent, in fig. 7, in which *c''* represents the ears, which serve to guide the work into the slot *c*, and *c'* represents the two limbs of the spring, which serve to keep the tuck folded as it passes in, and also assists in holding the work in place down upon the cloth-plate of the machine.

The spring, being bent in the middle, is inserted in the slot, and properly secured therein, with the lower edge of the limbs upon the same plane with the lower side of the bent arm *a*, and the ears *c'* being bent, as shown *m-c'*, in fig. 4, to assist in giving a free and easy passage to the goods through the slot *c*.

The bent arm *a* has the same shoulder *i*, against which the edge of the tuck passes, as is shown in the beforementioned Letters Patent, and the spring *a'* may also be attached in a similar manner.

The piece *b* has a slot, *b'*, therein, through which passes a thumb-nut, *b''*, securing it to the table or cloth-plate of a machine, and secured to the piece *b*, by means of the pivot or set-screw *f*, is an elbow, *s*, one end of which is bent upward at *s'*.

To this upright end of the said elbow *s* are pivoted, by means of the set-screw *s'*, or a thumb-nut, the small arms *t* and *t'*, the other end of the arm *t* being pivoted to the elevator *n*, at *r*, while the arm *t'* has a small pin or stud secured thereto, which slides to and fro in the slot *r'* made in the elevator-bar *n*, whenever the said bar *n* is raised or depressed.

To the elbow *s* is secured, by means of a set-screw, *h*, or thumb-nut, the bar *m*, which may be sufficiently thin as to be somewhat elastic, and a slot, *l*, is made therein, so that said bar may be adjusted at about a right angle to, and at any distance from the elevator-bar *n*, as shown in fig. 3, and the end of said bar *m* nearest the elevator is turned upward and backward a little, and the end so turned back is made somewhat sharp, so that as a plait which has been sewed passes along over the bar *m*, back of this sharp edge *o*, a slight pressure downward upon the plait will cause the plait to catch against the sharp edge and pass along against it, and thus prevent the goods from being pulled out of place, toward the elevator-bar *n*, and also serving as a guide to keep the tuck or plait which is being sewed, always at the same distance from the tuck which has been previously sewed.

The bar m may have any desirable scale marked thereon, to facilitate its adjustment in regulating the distance between the tucks or plaits.

The bent arm a has at the top a small horizontal groove, in which is secured, in any desirable position, the presser-guide d , by means of a set-screw, n , or by a thumb-nut.

The form of the presser-guide is shown more fully in fig. 6, in which d is the part which is secured in the groove or channel, and g is the pressing-arm, which may be at nearly right angles with the part d .

The part d is curved, as shown in fig. 2, so that the pressing-arm g is brought down to a position a very little lower than the sharp edge o , upon the bar m .

Another modification of the sharp-edged guide o is shown in fig. 9, in which n is a thin piece of metal, bent so as to clasp the bar m , and may be made to slide to and fro thereon; and to this piece n is attached the part o' , which is bent upward slightly above the bar m , and the edge o' is made sharp, like that upon the bar m .

There are other and equivalent modes of attaching and arranging the sharp edge to be used in connection with the tucker, but we prefer that herein shown, as being simple and effective.

The tucker might be operative, in a measure, if the spring a' were not attached, but we prefer to use it, as it assists greatly in turning the fold of the tuck over and down upon the cloth-plate of the machine, as it is being sewed, and the spring a' may not actually be required in sewing or making very wide tucks or plaits, but it is essential in making narrow ones, as it assists greatly in keeping the goods, down upon the cloth-plate and in keeping the two sides of the tuck together as it passes along and before it is sewed.

In attaching this tucker to a machine known as the Florence machine, a small screw is turned down through the presser-foot of the machine into the threaded hole e , and it is there perfectly secure, as shown in fig. 1, the red lines representing the presser-foot, and the cloth-plate being represented at A.

In attaching the tucker to the various other machines in use, we use variously constructed clamps, one modification of which is shown in fig. 8. This is attached to the upper side of the lower end of the bent arm a by a screw or thumb-nut passing through the hole o' into the threaded hole e' in the arm a , and the presser-foot passes through the space v , the projection x extending over a portion of the presser-foot, while the part D passes under the other part of the presser-foot.

The clamp shown in fig. 8 is designed to be used with the Singer sewing-machine, but the shape of the clamp may be the same for all machines now in common use, as it is only necessary that the space or recess v should be changed in form to suit the presser-foot of the machine upon which it is desired to be used.

The clamp is attached to the presser-foot of any machine, with the part x nearest the end of the bent arm a , in which is the needle-hole e , the point upon the extremity of the part x pointing in the same direction as the work moves, as indicated by the arrows in figs. 1 and 3.

By this means, the tucker may be attached to any of the sewing-machines in use, by simply varying or changing the form of the clamp-recess v , to conform to the particular construction of the presser-foot to which it is desired to attach the tucker, as the pressers of the different machines vary somewhat in their details.

The bent arm a is bent in either direction accord-

ing as the different machines require the work to be run from right to left, or from left to right.

In those machines which require the work to be run from left to right, as the Wheeler & Wilson machine, the arm a is bent in an opposite direction to that herein shown, while this is adapted to those machines which take the work in from right to left, as the Florence machine, and various others.

In this connection, we would mention that all sewing-machines now made, we consider as divided into two classes, as regards the movement of the feed, namely :

First, those in which the space under the needle-arm is to the left of the feeder, looking in the direction of the line of motion of the goods; and second, those in which said space is to the right of the feeder, looking in the direction of the line of motion of the goods; those in the first case representing the class requiring the work to be moved from left to right with reference to the needle-arm, while those in the second case represent the class requiring the work to be moved from right to left.

Having described the construction of our invention, we will now proceed to describe its mode of operation.

The first tuck may be marked and sewed, as in the ordinary method of making them, or it may be made by this tucker, by ganging by the edge of the cloth if it is convenient to do so.

The cloth is placed upon the elevator-bar n , (fig. 1 representing the whole device attached to a machine,) and the end of the cloth is passed along in the direction of the arrow and in between the ends of the spring a' , the tuck or plait which has just previously been made being passed in between the presser-guide g and the sharp edge o , and as the presser g presses gently upon the upper surface of the plait, the sharp edge o catches against the edge of the plait underneath, where it has been sewed, and as the goods pass along, the new tuck or plait is being sewed at the same equal relative distance from the last one; said distance being regulated by means of the sharp edge o upon the gauge m .

As the fold passes along through the spring a' and slot e , it passes against the oblique edge i of the bar a , upon one side of the fold, while the other side of the fold passes against the end of the spring a' , the arms c^2 of the spring a' assisting in guiding the fold along properly and in keeping the goods down upon the cloth-plate.

As the fold passes the oblique edge of the arm, the fold is pushed over and down upon the cloth-plate, one edge of the same—the under one—passing along against the shoulder i , upon the under side of the bent arm a .

The height of the top of the elevator-bar n , above the cloth-plate of the machine, regulates the width of the tuck or plait, and to facilitate the adjustment of the elevator-bar to any desirable height, to make a tuck of any certain width, a scale is marked upon the bent arm a , as shown in fig. 2, and as the elevator-bar is arranged to be always in a horizontal position, the cloth passes along upon it more freely than if one end were more elevated than the other, in which case the cloth is apt to catch, and does not pass into the spring a' freely.

In making very wide tucks or plaits, either the presser-guide g or the sharp-edged gauge might be omitted, and the cloth be guided by either pressing gently the tuck down against the sharp edge with the finger, or by running the cloth by the edge of the presser-guide g , whichever is used; but in making narrow tucks or plaits it is necessary that both should be used.

Having now described our invention, What we claim as new, and desire to secure by Letters Patent, is—

1. The spring *c*', having the arms *c*² and ears *c*" thereon, constructed and operating substantially as and for the purposes specified.
2. An elevator, constructed substantially as described, and arranged with the cloth-plate of a sewing-machine, so as to be always in a horizontal position, and adjustable to any desirable height from said cloth-plate, substantially as herein described and set forth.
3. The combination of the bar *m*, having the sharp edge *o* thereon, with the spring-presser *d g*, operating substantially as herein described and specified.
4. The combination of the elevator *n* with the

spring *c*' and bent arm *a*, having the guide or shoulder *i* thereon, all operating substantially as herein described and set forth.

5. The combination of the adjustable horizontal elevator *n* and bent arm *a*, all constructed and operating substantially as and for the purposes herein specified and described.
